UNITED STATES PATENT OFFICE.

TURNER J. DANIEL, OF BUTLER, ALABAMA.

HARNESS-CLASP.

1,089,625.

Specification of Letters Patent. Patented Mar. 10, 1914.

Application filed October 29, 1913. Serial No. 797,972.

To all whom it may concern:

Be it known that I, TURNER J. DANIEL, a citizen of the United States, residing at Butler, in the county of Choctaw and State of Alabama, have invented certain new and useful Improvements in Harness-Clasps; and I do hereby declare the following to be a full, clear, and exact description of the invention, such as will enable others skilled in the art to which it appertains to make and use the same.

My invention relates to new and useful improvements in clasps for harness and is particularly adapted for permitting adjustment of the back strap of a harness relative to the harness saddle.

An important object of the invention is to provide an adjustable clasp for harness which will permit ready adjustment of the harness and provides for the locking of the harness in adjusted position in a reliable expeditious manner.

Another object of my invention is to provide a device such as above described which is simple as to construction and arrangement of parts, light, strong and durable, may be readily attached to harness and is cheap to manufacture.

The above and additional objects are accomplished by such means as are illustrated in the accompanying drawings, described in the following specification and then more particularly pointed out in the claims which are appended hereto and form a part of this application.

With reference to the drawings, wherein I have illustrated the preferred embodiment of my invention as it is reduced to practice, and throughout the several views of which, similar reference numerals designate corresponding parts: Figure 1 is a detail perspective view of the adjustable locking plate forming a part of the invention, Fig. 2 is a detail perspective view of the fixed locking means adapted for coöperation with the locking plate, Fig. 3 is a longitudinal sectional view illustrating the device in assembled position, and Fig. 4 is a detail longitudinal sectional view illustrating the locking lever in locked position.

Coming now to the description of the drawings the numeral 1 represents as an entirety the fixed locking plate that is preferably constructed of thin metal and is substantially rectangular in shape. This plate

1 is adapted to be secured to the harness saddle not shown. A pair of opposed laterally extending ears 2 and 3 are formed integral with the plate 1 adjacent one terminal thereof and on the longitudinal edges thereof and are apertured so that suitable fastening means not shown may be inserted therethrough for the purpose of securing the plate to the harness saddle. The terminal of the plate farthest removed from the lateral ears 2 and 3 is reduced as at 4 and provided with an opening 5 adjacent its outer extremity so that suitable fastening means not shown may be inserted therethrough and into the harness saddle. It will thus be seen that the plate 1 is adapted to be secured to the harness saddle by the means above described.

A locking lever 6 is secured adjacent one terminal to a pivot pin 7 that is pivotally supported within a pair of upstanding ears 8 and 9 which are formed integral with the plate 1 in opposed relation and upon the longitudinal edges of the plate. The pivoted terminal of the locking lever 6 is provided with lugs 10 and 11 which are formed integral therewith in spaced relation to each other adjacent each side of the lever and extend at right angles thereto. These lugs 10 and 11 are adapted for engagement with an adjustable locking plate 12 which will be hereinafter more fully described, and serve to hold the locking plate 12 in locked position upon the fixed locking plate 1.

The adjustable locking plate 12 is constructed of the same material as the fixed locking plate 1 and is preferably rectangular in shape. The plate 12 is adapted for sliding adjustment upon the fixed plate 1 between the upstanding ears 8 and 9 and as a means for further guiding the sliding movement of the plate 12 and for holding it in proper alinement relative to the plate 1 there has been provided a pair of diametrically opposed guide flanges 13 and 14 that are formed integral with one terminal of the plate 1 adjacent the lateral ears 2 and 3 and are bent over to lie in parallel spaced relation to the upper surface of the plate, and a similar pair of guide flanges 15 and 16 that are formed integral with the plate at a point adjacent the one terminal of the upstanding ears 8 and 9 in diametrically opposed relation and are bent over in the same manner as are the flanges 13 and 14 thus it

will be seen that the plate 12 is, when mounted upon the plate 1, held in the proper position thereon for sliding movement.

One terminal of the adjustable locking plate 12 is provided with a plurality of hook members one of which designated 17 is inwardly turned and formed centrally of the side edges of the plate, the other two designated 18 and 19 are inwardly turned and formed integral with the longitudinal edges of the plate in diametrically opposed relation. Suitable parts of the breeching or back band may be secured to these hook members 17, 18 and 19.

As a means for locking the adjustable locking plate in adjusted position upon the fixed locking plate, reference being had particularly to Fig. 3 in the drawings, there has been provided a pair of spaced locking tongues 20 and 21 that are disposed in spaced relation to the upper surface of the plate and formed integral therewith. The locking tongues 20 and 21 are formed by making a long lateral slit centrally of the side edges of the plate 1 and short longitudinal slits at the terminals of the lateral slit then striking upwardly the slotted portions thus forming the locking tongues. The locking tongues 20 and 21 are disposed approximately centrally of the ends of the plate 1 so that the lugs 10 and 11 are disposed between them when in locked position.

The adjustable locking plate 12 is provided with a plurality of spaced rectangular openings 22 that are adapted to receive the locking tongues 20 and 21 when the device is in locking position. The locking and adjusting action of the device is briefly described as follows. Assuming that the adjustable plate 12 is mounted for sliding movement upon the fixed sliding plate 1 so that the guide flanges 13, 14, 15 and 16 are in engagement with the adjustable plate and the locking lever 6 is in a position such as illustrated in Fig. 2, the plate 12 is then moved to the desired adjusted position and as the openings 22 therein are approximately in the same spaced relation as are the locking tongues 20 and 21, the tongues 20 and 21 are inserted within the openings and the upper terminals thereof bear against the upper face of the plate 12. The locking lever 6 is then operated so that the lugs 10 and 11 are moved into bearing engagement with the upper surface of the plate 12 thus holding the plate in locked engagement with the locking tongues 20 and 21. A flange 23 is formed integral with the free terminal of the locking lever 6 and extends at right angles thereto. This flange 23 is adapted to seat within one of the openings 22 when the locking lever 6 is moved in locked position as illustrated in Fig. 3 in the drawings and serves to assist the lugs 10 and 11 in securely

holding the plate 12 in locked position upon the fixed plate 1 as will be clearly seen with reference to Fig. 3 in the drawings.

To unlock the plate 12 from the plate 1 the lever 6 is moved to a position such as illustrated in Fig. 2 and the plate 12 is then free to be moved out of engagement with the locking tongues 20 and 21 and this is done by pushing it forwardly relative to the locking tongues and then pulling it away from the plate 1 there being sufficient space between the lever 6 and plate 1 to permit such action.

It will be apparent with reference to the foregoing description and accompanying drawings that a clasp for harness is provided which will permit the ready and effectual adjustment of the harness and afford a reliable and efficient locking means for locking the harness in adjusted positions in a reliable manner so that accidental derangement of the locking means is positively prevented.

In reduction to practice, I have found that the form of my invention, illustrated in the drawings and referred to in the above description, as the preferred embodiment is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

What is claimed is:—

1. A clasp for harness comprising a stationary locking plate, an adjustable locking plate having a plurality of spaced openings therein slidably mounted upon said stationary locking plate, a locking lever pivoted upon said stationary plate, a pair of spaced locking tongues disposed in spaced parallel relation to the upper surface of the stationary plate and formed integral therewith, harness securing hooks carried upon one terminal of said adjustable plate, spaced lugs carried upon the pivoted terminal of said locking lever and adapted for engagement with the adjustable plate when in locked position, said locking tongues adapted for engagement with the openings in the adjustable plate and guide means carried by said stationary plate.

2. A clasp for harness comprising a stationary locking plate, an adjustable locking plate mounted for sliding movement on said stationary locking plate and having a plurality of spaced openings formed therein, a pair of upstanding opposed ears formed on said stationary plate, a locking lever pivoted within the ears, a pair of spaced locking tongues formed integral with the stationary

plate and disposed in parallel spaced relation at their outer terminals to the upper surface of the stationary plate and adapted for engagement with the openings in the 5 adjustable plate, means for guiding said adjustable plate and holding it in sliding relation to the stationary plate and means carried upon each terminal of the locking lever for holding the adjustable plate in locked 10 position adapted for engagement with the locking plate and openings therein respectively.

3. A clasp for harness hooks comprising a rectangular stationary locking plate, an 15 adjustable locking plate adapted for sliding movement upon said stationary plate and having a plurality of spaced openings formed therein, a pair of opposed harness hook members formed integral with the adjustable 20 plate at one terminal thereof, an inwardly turned hook member formed integral with the adjustable plate and extend-

ing outwardly from one terminal thereof, a locking lever pivotally secured to said stationary plate, a pair of lugs formed integral with the locking lever, adjacent the pivoted terminal thereof extending at right angles to the locking lever and adapted for engagement with the adjustable locking plate, a pair of spaced locking tongues 30 formed integral with the stationary plate and adapted for engagement with the openings in the adjustable plate, guide means carried by said stationary plate and means carried by the free terminal of said locking 35 lever and adapted for engagement with one of the openings in the adjustable plate to hold said plate in locked position.

In testimony whereof I affix my signature in presence of two witnesses.

TURNER J. DANIEL.
